BOTTLE

Robert J. Palazzo, Dallas, Tex., assignor to Anderson, Clayton & Co., Dallas, Tex., a corporation of Delaware

Filed Oct. 18, 1961, Ser. No. 67,148

Term of patent 14 years

(Cl. D58—6)

Fig. 1.

Fig. 2.

Fig. 3.

Fig. 4.

FIGURE 1 is a side elevational view of a bottle showing my new design, the ornamental detail being continuous around the bottle, and the opposite side being the same;

FIGURE 4 is a section view taken along the line 4—4 of FIGURE 1, illustrating particularly the outwardly projecting nature of the ribs formed about the shoulder portion of the bottle.

I claim:

The ornamental design for a bottle, as shown and described.
